UNITED STATES PATENT OFFICE

ANDREW J. WECKER, OF DAYTON, OHIO

DOORSTOP

Application filed August 6, 1928. Serial No. 297,704.

My invention relates to door stops, and more particularly to a duo-functional device, adapted in alternate position to secure a door in closed position and to hold the door when open against closing movement.

In the present construction, there is employed a reciprocatory detent rod mounted for to and fro sliding motion in a guide sleeve, which is pivoted for swinging motion upon a transverse axis. When in a vertical position, the detent rod is projected through a fixed keeper upon the door into engagement with a socket in the door sill. Upon withdrawing the rod from the socket and from the fixed keeper, and pulling it to an extreme position, through the swinging guide sleeve, the latter may be turned about its transverse pivotal connection to present the rod in a reversed inclined position relative to the door in which it will engage with the surface over which the door swings to act as a brace to hold the door against closing movement.

The object of the invention is to simplify the construction as well as the means and mode of operation of door stops and swinging closure fasteners, whereby, they will not only be cheapened in construction, but will be more efficient in use, positive in operation, easily adjusted, and unlikely to get out of repair.

A further object of the invention is to provide a door stop which will securely hold a swinging door in different positions of adjustment to prevent its closing movement.

A further object of the invention is to provide a single detent element capable of operation in alternate positions, to secure the door against opening movement when closed, and when open to secure the door against closing movement.

A further object of the invention is to provide a reversible stop element and a mounting therefor, enabling quick and easy operation of the stop element from one position to another.

A further, but none the less important object of the invention, is to provide such a door stop device, the parts of which are so designed and arranged as to be cheaply and economically manufactured, and which may

be easily and quickly installed by an unskilled person.

With the above primary and other objects in view, as will more fully appear in the specifications, the invention consists of the features of construction, the parts and combinations thereof, and the mode of operation or their equivalents, as hereinafter described and set forth in the claims.

Referring to the drawings, in which is shown the preferred, but obviously not necessarily the only form of embodiment of the invention, Fig. 1 is a perspective view of a portion of a closed door to which the door stop, forming the subject matter hereof, has been applied. Fig. 2 is a similar perspective view showing the door stop in its reversed position, holding the door open. Fig. 3 is a longitudinal sectional view of the assembled door stop in its normal locking position. Fig. 4 is a detail sectional view showing a portion of the stop rod and its mounting in reverse position. Fig. 5 is an auxiliary stop arm, which may be used in connection with the locking device.

Like parts indicated by similar characters of reference throughout the several views.

Referring to the drawings, 1 is a swinging door to which is secured a supporting bracket 2, having parallel spaced ears 3. Pivoted between the ears 3 is a guide sleeve or keeper 4 mounted for swinging movement upon a transverse axis. The guide sleeve 4, is counterbored and affords at one end a bearing for a reciprocatory detent rod 5. One end of this rod is preferably pointed or sharpened as at 6, while the opposite end of the rod is provided with a peripherally enlarged head 7.

Fixedly secured to the lower portion of the door 1 in spaced relation below the bracket 2, is a fixed guide or keeper 8 having therein an opening in axial alignment with the guide sleeve 5, through which the enlarged head 7, of the locking rod 5 may be projected into a socket 9 in the door sill or in the floor beneath the door. A collar 10 upon the rod 5 limits its reciprocatory motion through the swinging guide sleeve 5 in one direction. The head 7 limits such movement of the rod

5 in the opposite direction. The collar 10 is sufficiently large to serve as a handle or knob by which the rod 5 may be lifted to disengage it from the socket 9 when the door is 5 to be opened. If the door is to be merely released, and not propped, the rod may be lifted by the operator, engaging and raising the collar 10 with his foot without the necessity of stooping.

10 When the door is to be secured in its open position, the rod 5 is withdrawn through the swinging guide sleeve 3 to the full limit of its stroke. In its extreme position, the head 7 enters within the counterbore of the guide sleeve a sufficient distance to permit the end 15 of the rod to clear the door 1 and bracket 2 as the swinging guide sleeve oscillates upon its transverse pivotal connection. When in this extreme position, the rod and guide 20 sleeve are swung outwardly and downwardly to the position shown in Fig. 2. In such position, the sharpened end 6 of the rod engages with the ground or floor over which the door swings while the head 7 of the rod 25 abuts upon a lug 11 which is a part of the supporting bracket 2. For economy of manufacture, this abutment lug 11 has been shown as a reversed tongue of metal stamped from the base of the bracket 2. It will be 30 understood, however, that such construction is merely incidental and that the lug may be otherwise formed, or may be entirely omitted, and the rod permitted to abut upon the base of the bracket 2.

35 To provide a spaced bearing for the detent rod 5, and prevent wobble movement of the rod in the guide sleeve 4, there is loosely mounted in the counterbore of such guide sleeve a washer or collar 12 surrounding the rod 5. The end of the guide sleeve 4 is provided with a bushing ring 13, pressed, threaded, or otherwise secured in place, which limits the outward movement of the washer or collar 12, and also provides a bearing 40 engaged by the enlarged head 7 of the rod when the latter is retracted. The bore of the bushing ring 13 being somewhat larger than the rod 5 would not securely support the rod when the latter is extended. The washer or 45 collar 12 drops by gravity to a position contiguous to the bushing ring 13 when the guide sleeve is upended as in Figs. 1 and 3. However, upon the retraction of the detent rod 5, the enlarged head 7 entering within the bore 50 of the bushing ring 13 engages the washer or collar 12 and lifts such washer or collar 12 in unison with the retractive movement of the locking rod 5. In such retracted position, the detent rod thus has bearings both 55 in the counterbored guide sleeve 4 and in the bushing ring 13. When extended as in Figs. 1 and 3, it has bearing in the guide sleeve 4 and in the collar or washer 12.

60 If it be desired to employ the present door stop for fastening purposes only, and not to

secure the door open, a bifurcated bracket arm 14 is secured to the door 1 with its arms straddling the rod 5 at such height as to be engaged by the head 7 of the rod when withdrawn from the socket 9, but before the 70 rod 7 has been withdrawn from the fixed guide or keeper 8. To hold the device against rattle or clatter, there is provided a small spring actuated plunger 15 housed in a hollow boss formed in the upper end of 75 the supporting bracket 2. This spring actuated plunger 15 bears against the swinging guide sleeve 4, when the latter is in its normal or upright position, with sufficient pressure 80 to prevent vibration or rattle.

The construction as described, provides a simple, compact, and easily operated device which in one position engages with the socket to secure the door in closed position, and is capable of being easily and readily reversed 85 to downwardly and outwardly inclined position in which it will drag over the surface over which the door swings as the door opens, and will automatically engage such surface 90 to prevent return swinging movement of the door.

From the above description it will be apparent that there is thus provided a device of the character described possessing the particular features of advantage before enumerated 95 as desirable, but which obviously is susceptible of modification in its form, proportions, detail construction and arrangement of parts without departing from the principle involved or sacrificing any of its advantages. 100

While in order to comply with the statute the invention has been described in language more or less specific as to structural features, it is to be understood that the invention is not limited to the specific details shown, but that the means and construction herein disclosed comprise the preferred form of several modes of putting the invention into effect and the invention is, therefore, claimed in any of its forms or modifications within 110 the legitimate and valid scope of the appended claims.

Having thus described my invention, I claim,

1. In a door stop of the character described, 115 a reciprocating rod, a guide sleeve in which the rod is mounted for sliding motion, a bracket in which the guide sleeve is mounted for swinging motion about a transverse axis, a head upon the rod limiting its reciprocating movement relative to said sleeve, said guide sleeve being counterbored, a bearing collar loosely surrounding the rod within the bore of said guide sleeve and movable to and fro therein, stop means preventing the escape 120 of the collar from the guide sleeve, said guide sleeve being reversible upon its pivotal bearing upon the retraction of the rod, to present said rod in an inclined position, and a stop shoulder upon the bracket upon which 125 130

the end of the rod abuts when in such inclined position.

2. In a door stop of the character described, a reversible reciprocatory detent rod, carried by the door one end of which is engageable in a socket in the door sill to maintain the door closed, the other end of which is engageable with the surface over which the door swings to maintain the door open, and a pivotally mounted guide for the rod in which the rod is mounted for reciprocatory motion, by the swinging adjustment of which the rod is reversible.

3. In a door stop of the character described, a reciprocatory detent rod, engageable in a keeper socket to maintain the door closed, a guide sleeve in which the rod is mounted for to and fro sliding motion, a bracket in which the guide sleeve is mounted for swinging motion about a transverse axis, said guide sleeve being reversible upon its pivotal connection upon retraction of said rod, to present the rod in a reverse inclined position, for engagement with the surface over which the door swings to maintain the door open.

4. In a swinging door stop, a reversible reciprocatory detent rod one end of which is substantially perpendicularly engageable with the surface over which the door swings to lock the door closed and the other end of which is engageable with the surface over which the door swings in an inclined position of the detent rod thereto to maintain the door open, and a pivotally mounted guide for the rod in which the rod is mounted for reciprocatory motion, the rod being reversible by reversal of the guide upon its pivotal bearing.

5. In a door stop, a reciprocatory detent rod, a pivotally mounted guide therefor in relation with which the rod is capable of to and fro longitudinal movement, and a retractile bearing for said rod carried by the guide, said rod being reversible upon retraction of the rod relative to the guide by reversal of the pivotal guide.

6. In a door stop, a duofunctional reciprocatory detent rod, a swinging guide therefor in relation with which the rod is capable of to and fro longitudinal motion, said rod being vertically engageable with the surface over which the door swings to secure the door in closed position and after swinging adjustment about the pivotal connection of the swinging guide, said rod being further engageable with said surface in an inclined position to maintain the door open.

7. In a door stop, a reciprocatory rod, and a pivotally mounted guide for said rod in which the rod is mounted for limited to and fro movement, said guide comprising a sleeve having at one end a perforated guide head through which the rod extends, a collar surrounding said rod and slidale thereon within said sleeve, a stop limiting the outward

movement of the collar relative to the sleeve, and a peripheral shoulder on the rod engaging with said collar when the rod is moved in one direction.

8. In a door stop a reciprocatory detent rod, a counterbored guide sleeve for the rod having a fixed bearing at one end of the sleeve, and a second bearing member for the sleeve normally in distantly spaced relation with said fixed bearing to afford an extended bearing for said rod, said second bearing being axially adjustable within the bore of the guide sleeve, upon retraction of the rod to afford ample clearance for said rod substantially as specified.

9. In a door stop, a reciprocatory detent rod, a peripherally enlarged head thereon, a guide sleeve, a fixed bearing in which the rod is mounted for reciprocatory motion, said sleeve being counterbored to receive said head, and an axially movable bearing member within the bore of said guide sleeve and normally located in spaced relation with said fixed bearing to afford an extended bearing for said rod, said bearing member being retractable by the engagement of the head therewith to afford increased clearance for the head of said rod.

10. A door stop for a swinging door including a single detent member and a mounting therefor, the detent being engageable alternately in perpendicular and inclined securing engagement with the surface over which the door swings for holding the door closed when in one such position of adjustment and holding the door open when in the other such position of adjustment.

11. A door stop for a swinging door including a single reversible detent member and a mounting therefor in which the detent member is capable of both reciprocatory and oscillatory motion, the opposite ends of the detent being alternately engageable with the surface over which the door swings in alternate perpendicular and in inclined relation of the detent thereto to hold the door in closed position and in open position respectively.

In testimony whereof, I have hereunto set my hand this 21st day of July, A. D. 1928.

ANDREW J. WECKER.
